PATRICK LENNOX, HIRAM H. ROBBINS, AND EDWARD HAYES, OF LYNN,
MASSACHUSETTS.

Letters Patent No. 78,380, dated May 26, 1868.

IMPROVED MACHINE FOR BEAMING HIDES.

The Schedule referred to in these Letters Patent and making part of the same.

TO ALL TO WHOM THESE PRESENTS SHALL COME:

Be it known that we, PATRICK LENNOX, HIRAM H. ROBBINS, and EDWARD HAYES, of Lynn, in the county of Essex, and State of Massachusetts, have invented a new and useful Improvement in Machines for Beaming Hides, as well as for scouring and sleeking leather; and do hereby declare the following to be a full, clear, and exact description thereof, due reference being had to the accompanying drawings, making part of this specification, and in which—

Figure 1 is a side elevation,

Figure 2 a plan,

Figure 3 a rear end elevation of the said invention.

This invention is an improvement in machines for beaming hides or skins, or for scouring and sleeking leather, and relates to means for holding such hides in a manner to enable the whole hide to be beamed or manipulated at one operation of the machine, in contradistinction to the mode shown in the machine constituting the subject of Letters Patent, No. 70,268, and dated the 29th day of October, 1867, in which one-half only of the hide is subjected at once to the action of the beaming-tool, necessitating the removal of the skin from the machine, and turning it about, end for end.

Our present machine, in its general characteristics, like the one before mentioned, is composed of a reciprocating carriage or head, carrying a beaming-tool, and duly supported upon a proper frame or standard, such reciprocating tool operating in connection with a movable car, for supporting the skin under the action of the tool, the car having a revolving or swivelling movement imparted to it by the workman, as occasion requires.

Our invention consists in the employment of a pressure-bar or friction-brake, affixed to the outer ends of two levers, pivoted to the opposite sides of the supporting-slides of the beaming-tool carrier, and in advance of such carrier, and actuated by the driving-power of the machine, in such manner as to press upon the hide with a powerful pressure, while the beaming-tool is acting upon it, and hold it to the tablet upon which it rests, with sufficient power to prevent it from being displaced by the draught of the beaming-tool.

The invention further consists in a novel mode of applying the tool-carrier to its carriage by means of springs, in manner and for the purpose as hereinafter explained.

In the drawings above mentioned as illustrating our invention, the frame of the machine is shown at A, as composed of two upright twin standards, *a a*, each of such standards having a long horizontal extension, *b b*, projecting from its upper part, these extensions *b b* being parallel to each other, and serving as ways or guides to a sliding carriage or cross-head, C, which is disposed between them, and so as to slide freely thereon, the necessary reciprocating rectilinear movements of such carriage being effected by a connecting-rod, *d*, one end of which is pivoted to the carriage, and its opposite end to a wrist-pin, *a'*, connecting the two contiguous ends of two twin cranks, *e e*, which are supported at about their centres upon the inner extremities of two horizontal shafts, *ff*, duly supported in boxes *g g*, applied to the upper part of the standards *a a*, before mentioned, the said cranks *e e* being balanced cranks.

The outer end of one of the shafts *ff* carries fast and loose pulleys, *h h'*. The sliding carriage *e* has four depending posts, *i i i i*, upon which is supported a plate, *j*, in such manner as to move freely up and down upon such posts, a spiral spring, *k*, being coiled about each post *i*, the plurality of springs serving, by their extensions, to force the plate *j* down with considerable force.

The beaming-tool carrier or head is shown at *l*, as pivoted to the under side of the plate *j*, and so as to be capable of longitudinal vibrations thereon, the said carrier *l* being provided with a beaming or fleshing-tool, *m*, as represented.

Furthermore, to the rear side of the tool-carrier *l* is pivoted one extremity of a curved eccentric-rod, *n*, the opposite end of such rod carrying an eccentric-strap, *o*, which encompasses an eccentric-block, *p*, applied

eccentrically to the wrist-pin a' , before mentioned, the disposition of the eccentric-block p , with respect to the beaming-cranks and the tool-carrier, being such that during a forward movement of the said tool-carrier, its beaming-tool shall be raised into an angular position above the surface of the hide, and free from contact with it, and during a reverse or rearward movement of the tool-carrier, it shall maintain the beaming-tool in an upright and rigid position, and by lowering its working-edge, bring it forcibly in contact with the surface of the hide.

As the operation of the beaming-tool upon the hide is well known, and has been described in Letters Patent before referred to, as granted to Lennox and Roberts, further description of its action is not considered necessary.

We wish it to be understood that the present machine is to have applied to it, when in use, a movable car, for supporting the hide, constructed substantially as shown in Letters Patent before mentioned, with the exception that the revolving hide-supporting tablet of the car will be applied to its truck in nearly or quite an unyielding, inflexible manner, in order to withstand the pressure of the clamp or brake, to be hereinafter described.

The effect of this brake is to hold the hide securely to the tablet during the manipulations of the beaming-tool, and consists of a cross-bar, q , pivoted or otherwise applied to the lower ends of two hanging arms, $x x$, the upper ends of which are, in turn, pivoted to the outer extremities of two long vibrating-levers, $s s$, pivoted to the outer sides of the guides $b b$, before mentioned, the fulcra $t t$ of such levers being situated at about one-third their length from their outer ends, though in practice it may be found desirable to have this fulcrum an adjustable one, in order to vary the pressure of the brake upon the hide.

The opposite or inner ends of the levers $s s$ rest upon the periphery of two wipers, $w w$, fixed to the shafts $f f$, before referred to.

The form of these wipers, as shown in fig. 1 of the drawings, being the segment of about two-thirds of a circle, the disposition of the plane portion, v , of the wipers, with respect to the levers $s s$ and the beaming-tool and its carrier, being such that during a forward movement of the beaming-tool, the brake-bar q shall be raised above the surface of the hide, and during the return movement of such beaming-tool, or while it is scraping the hide, the circular or longer portion of the wipers, acting upon the levers $s s$, shall force the brake down upon the hide with considerable pressure, and hold it firmly upon the operating-tablet of the car.

The levers $s s$ are retained in contact with the peripheries of the wipers by means of coil-springs, or their equivalents, suitably connected with them and the frame of the machine.

The object of the before-described arrangement of the two cranks $e e$, supported upon the shafts $f f$, and with the rods d and n , enclosed between them, is to obtain great strength of parts, and an equal, steady motion of the machine, which could not be the case were the rods d and n applied to one crank, or to the face of a wheel.

The object in applying the tool-supporting plate or bracket j to the sliding carriage C , as described, is to allow of the necessary elasticity in the pressure of the beaming-tool upon the hide, for the reason, as before observed, that the removal of this elastic feature from the hide-supporting car renders its application to the tool necessary.

By the employment of a brake or device for clamping the hide to the table, as described, the capacity of the machine for labor is doubled, as the time formerly occupied in reversing the hide, after one-half of it had been manipulated, is by this means saved and economized, as the entire circuit of the hide by the beaming-tool is accomplished without changing the position of the hide upon its tablet.

As the beaming-tool acts upon the hide from its centre, radially outward during the revolution of the tablet, such hide is treated in a more uniform and desirable manner than has heretofore been accomplished.

We claim as our invention, and desire to secure by Letters Patent of the United States, as follows:

1. In a machine for beaming hides or dressing leather, we claim a device so constructed and applied thereto as to automatically press upon or clamp the hide to its supporting-table, and hold it in position under the action of the beaming-tool, in order to manipulate the hide at one operation.

2. We claim, as a device for accomplishing the above result, the combination and arrangement of the brake-bar q with the vibrating-levers $s s$, such levers being pivoted to the guides $b b$, and actuated by the wipers $w w$, and operating in connection with the beaming-tool, essentially in manner and for the purpose as herein shown and described.

3. We claim the mode of suspending the beaming-tool from the sliding carriage c , that is, by means of the plate or bracket j , posts $i i$, and springs k , &c., substantially in manner and for the purpose as herein shown and described.

4. We claim the arrangement or disposition of the twin cranks $e e$, as supported by the shafts $f f$, and carrying between them the two rods d and n , and eccentric, p , essentially as herein set forth and explained.

PATRICK LENNOX,
HIRAM H. ROBBINS,
EDWARD HAYES.
